US00D917310S

(12) **United States Design Patent** (10) **Patent No.:** **US D917,310 S**
Kaneko (45) **Date of Patent:** **** Apr. 27, 2021**

(54) **WATCH**

(71) Applicant: **Citizen Watch Co., Ltd.**, Nishitokyo (JP)

(72) Inventor: **Shoya Kaneko**, Higashimurayama (JP)

(73) Assignee: **Citizen Watch Co., Ltd.**

(**) Term: **15 Years**

(21) Appl. No.: **29/722,631**

(22) Filed: **Jan. 31, 2020**

(51) LOC (13) Cl. **10-02**

(52) U.S. Cl. **USPC D10/39**
